METALLIC JAR

Knute G. Anderson, Rockford, Ill., assignor to
 J. L. Clark Manufacturing Co., Rockford, Ill.,
 a corporation of Illinois

Application February 26, 1938, Serial No. 192,712

2 Claims. (Cl. 220—10)

The invention relates to small jars of the type employed as containers for cold cream, ointments, and the like and has particular reference to double-walled containers of the type shown in 5 Patent No. 2,044,093, issued June 16, 1936.

In the aforesaid patent there is disclosed a metallic jar composed of inner and outer sheet-metal shells with the inner shell projecting above the outer shell and providing a threaded neck 10 portion for the reception of a screw cap. Because the inner shell, in the patented construction, is frictionally held against rotation relative to the outer shell, difficulty has been experienced in removing the cap, the frictional connection 15 being in some instances ineffective to prevent turning of the inner shell with the cap.

In a copending application of Wallace C. Mills, Serial No. 109,067, the aforesaid difficulty is overcome by a construction in which the threaded neck portion is formed integral with the outer shell rather than the inner shell, but in view of 20 certain advantages inherent in the patented construction in which the threaded neck is integral with the inner shell, the present invention has 25 for its primary object the production of a jar or container of the type shown in said patent providing in a simple and effectual manner a positive interlock between the shell so as to hold the inner shell against rotation relative to the outer shell while screwing the cap on or off.

More particularly the invention resides in the utilization of a longitudinal seam on the outer shell in providing for an interlock between the two shells.

Further objects and advantages of the invention will become apparent as the following description proceeds and the features of novelty which characterize the invention are pointed out with particularity in the claims annexed to and 40 forming a part of this specification.

For a better understanding of the invention, reference may be had to the accompanying drawings in which,

Figure 1 is a perspective view of a sheet metal 45 container embodying the invention.

Fig. 2 is a central vertical sectional view of the container shown in Fig. 1.

Fig. 3 is an enlarged fragmentary transverse 50 sectional detail view taken approximately in the line 3—3 of Fig. 2 and illustrating the manner in which the aforesaid interlock is obtained.

For purposes of illustration, the invention has been shown as embodied in a jar or container particularly adapted for cold cream or similar 55 viscous cosmetics and the like. The particular

container illustrated comprises outer and inner shells designated generally by the numerals 10 and 11, respectively, and a cooperating closure cap 12.

The outer shell comprises a peripheral side wall 13 and a bottom wall 14. The side is formed from a flat sheet of metal rolled into cylindrical form with the edges of the sheet joined in an interlocking seam 15; and the bottom wall is formed from a metal disk resting upon the edge 10 of an inwardly curled flange 16 at the lower end of the outer shell. Preferably the seam 15 terminates short of the outer side wall 13 to accommodate the bottom wall 14. At its upper end the peripheral side wall 13 terminates in an inwardly 15 bent or curled bead 17.

The inner shell, which is made of a diameter somewhat less than the diameter of the outer shell has a bottom wall 18 and a peripheral side wall 19. To retain the inner shell in centered relation 20 to the outer shell with an air space 20 therebetween, the bottom wall 14 of the outer shell is herein shown as formed with a depression 21 shaped to receive the bottom wall of the inner shell.

To avoid the formation of any joints or crevices, the inner shell is drawn from a single sheet of metal and its upper end portion terminates in a flange bent outwardly and downwardly to form an integral neck portion or sleeve 22 having a 30 smooth rounded upper end 23. The sleeve 22 projects downwardly to a point within the upper end of the outer shell and its lower edge is flared outwardly as at 24 into engagement with the inner and under side of the turned bead 17 at the 35 upper end of the outer shell. As shown the sleeve 22 is preferably spaced a short distance outwardly from the peripheral side wall 19, thus broadening the upper rounded end 23. At its lower end the sleeve is surrounded by the bead 17 of the outer 40 shell so that the upper face of said bead forms an upwardly facing shoulder for cooperation with the cap 12.

The cap 12 is preferably formed with a bowed top 25 and an annular skirt 26 having an integral 45 reverse flange 27. This flange provides an internal sleeve which is formed with a suitable screw thread 28 for cooperation with the sleeve 22 which is correspondingly threaded as indicated at 29. The proportions are such that the smooth outer 50 peripheral surface of the cap skirt 26 is disposed flush with the outer surface of the peripheral side wall 15 of the outer shell.

For the purpose of providing an interlock between the two shells positively preventing rela- 55

- tive rotation therebetween, I utilize the seam 15 of the outer shell. As shown in Fig. 3 this seam is so formed as to lie wholly within the outer periphery of the outer shell and therefore provides in effect an inwardly projecting element or rib upon the inner side of the outer shell. To receive this rib the flared end portion or flange 24 of the sleeve 22 is cut to form a notch 30. Thus it will be seen that in the operation of screwing the cap 12 onto or from the neck portion of the container, any tendency of the inner shell to turn relative to the outer shell is prevented by the engagement of the sides of the notch 30 with the sides of the seam 15.
- 15 I claim as my invention:
1. A double-walled sheet metal container comprising an outer shell having a side wall formed from a flat sheet of metal rolled into cylindrical form and joined in an interlocking vertical seam, an inner shell having an upright side wall spaced inwardly from the side wall of the outer shell and having a neck portion depending from its upper

end into the upper end of the outer shell, said seam of the outer shell projecting inwardly to form an elongated internal rib, and said neck portion on the inner shell having a flange notched to receive said rib.

2. A double-walled sheet metal container comprising, in combination, an outer shell having a side wall formed from a flat sheet of metal rolled into cylindrical form and joined in a longitudinal seam, a cup shaped inner shell fashioned from a single sheet of metal to form a smooth uninterrupted inner surface, said inner shell being telescoped within said outer shell, with the side walls of said shells in spaced relation, an integral neck portion on said inner shell depending from its upper end into the upper end of the outer shell, at least a portion of the seam on said outer shell projecting inwardly to form a rib, and said neck portion of the inner shell having a flange notched to receive said rib.
